GATE-COACTING RELIEF MECHANISM.

1,202,310.

Specification of Letters Patent Patented Oct. 24, 1916.

Application filed September 2, 1909. Serial No. 515,890.

To all whom it may concern:

Be it known that I, ARNOLD PFAU, a citizen of the Republic of Switzerland, residing at Milwaukee, in the county of Milwaukee and State of Wisconsin, have invented certain new and useful Improvements in Gate-Coacting Relief Mechanism, of which the following is a specification.

This invention relates to improvements in 10 the construction of gate-coacting relief mechanisms.

A clear conception of the invention can be obtained by referring to the accompanying drawing in which like reference characters 15 denote the same parts in different views.

Figure 1 is an elevation of the regulator shown applied to a hydraulic turbine. Fig. 2 is an enlarged central vertical section of the regulating dash pot. Fig. 3 is a similar 20 section of the regulating valve complete.

The by-pass valve consists of the elbow 1 which makes connection to the pipe line, turbine casing or impulse wheel nozzle and to the final discharge. The elbow 1 is located near 25 the turbine gate or main valve, and is provided with a relief valve 6 which controls the discharge of fluid from the pipe line on the inner or pressure side of the main valve, to the final discharge. The elbow carries 30 the cylinder 3 cast in one piece with it. Working in the cylinder is the piston 4 to which is attached through the rod 5 the disk valve 6. The water pressure in the elbow tends to force the disk valve 6 down 35 and thereby release the pressure by discharge through bypass, but the piston 4 is designed of sufficient area so that with pressure applied underneath it, the disk valve 6 will be pressed to its seat and thus held 40 closed. It is evident that if the pressure below piston 4 be reduced in cylinder 3, the disk valve 6 will open, due to penstock pressure, and that through variation of this 45 cylinder pressure we may move the disk valve 6 at will. The governing apparatus performs the function of automatically controlling the pressure in the cylinder 3 as required to operate disk valve 6 so as to prevent pressure changes in the pipe line caused 50 by sudden closing of the turbine gates or impulse wheel needle by the governor.

The cylinder 3 and piston 4 constitute relay mechanism for fluid pressure actuation of the by-pass valve 6. This relay mechanism is one of the important features of

this invention because its speed of operation is independent of the turbine main gate actuation. This permits of the use of a smaller by-pass than otherwise because its beginning of opening may be delayed and its speed of opening may be increased so that it will even with such delay be wide open before the turbine main gate reaches the limit of its closing motion.

A bell crank lever is connected at one of its arms, 9, to the gate shaft of the turbine or needle of the impulse wheel and at the other arm 11 to dash pot casing 12 and thus transmits the gate motion, thus raising or lowering the dashpot casing 12, and accordingly raising by positive pressure, or lowering, piston 13, piston rod 14, floating lever 15 and valve stem 16 with the valve 19 controlling the exhaust of water pressure from cylinder 3.

The cylinder 3 is connected with the interior of the casing 27 at a point below the seat of the valve 19 by means of a connection 8, while the interior of the casing 27 above the valve seat is connected with the exhaust 20 by means of a conduit 7. The conduit 2 connects the interior of the casing 27 with the penstock or turbine supply pipe line, being controllable by means of an adjustable needle valve 24. The positive raising of piston 13 is controlled by needle valve 18. The motion of the disk valve 6 is transmitted to the floating lever 15 by means of relay rod 17 projecting through the top cover of the relief mechanism.

Whatever position rod 14 takes, the disk valve 6 will be in a corresponding position due to the relay rod 17 and pin-connected floating lever 15. For instance, if the rod 14 be raised to a new position, the valve 19 will 95 be opened to a greater extent. This will relieve the pressure below the valve and below piston 4, permitting the penstock pressure on the upper side of disk valve 6 to open same. This moves relay rod 17 downwardly and consequently moves valve 19 toward closed position an amount sufficient to build up the pressure below piston 4 by closing off more the relief of pressure from the regulating valve chamber. This building up of pressure below piston 4 counteracts the pressure on disk valve 6 and permits it to assume a position corresponding to the new raised position of rod 14. If the piston rod 14 were rigidly coupled with the 100

dashpot casing 12, it is evident that the disk valve 6 would move synchronously to the motion of turbine gates or impulse wheel needle, it being assumed there is no delay in the action of the fluid pressure relay due to small passages and ports.

5 The gate mechanism 23 of the turbine illustrated in the drawing comprises the gates proper, not shown, and operating mechanism, conventionally shown. The relief mechanism would thus operate as a synchronous by-pass which closes when the turbine gate opens and opens when the turbine gate closes. Generally, however, this rod is not rigidly coupled with the dashpot casing. The dashpot has an adjustable by-pass valve 18 which controls flow of oil through the by-pass from bottom to top of piston 13. It is evident that when the motion of shaft 10 is slow enough, all the oil will flow through the by-pass without generating sufficient pressure below the piston 13 to raise same. The valve 19 and consequently the disk valve 6 will also remain closed.

25 When the motion is quick enough to generate sufficient pressure of oil under the piston 13, the latter will be raised as also valve 19 and consequently disk valve 6 will be caused to open approximately synchronously with the gate motion. This opening motion of valve 6 will compensate to close the regulating valve 19 by the action of the floating lever 15. The dashpot by-pass allows the oil to pass on top of piston 13, due to the weight 30 of piston 13, rod 14, valve stem 16, valve 19 and floating lever 15 moving about the pivot between relay rod 17 and floating lever 15, thus gradually closing the disk valve 6 by the gradual increase of pressure below piston 35 40 45 50 55 60 65 70 75 80 85 90 95 100 105 110 115 120 125 130

While the disk valve 6 closes slowly only as long as the gates of the turbine or needle of impulse wheel remain stationary after having moved quickly in closing direction, provision is also made to cause a synchronous closing of the disk valve 6 as soon as the gates are again moved in opening direction. If this opening of the gates is effected in a shorter time than that of the slow closing of disk valve 6 as above explained, or, in other words, if the gates begin to open again before the disk valve 6 has had time to be closed and before the valve 19 has been seated, the disk valve 6 will also close in approximately the same shorter period of time. This is effected by the downward motion of the dashpot and of piston 13 which will cause the opening of a large by-pass directly through the piston, thus enabling it to drop

synchronously with the motion of the gates and thus quickly placing the dash pot 12 in lowest relation to the piston so that the apparatus will be in condition to open the disk valve 6 should occasion require the closing of the gates immediately after their opening. At the same time the theretofore slowly closing valve 19 will be permitted, by gravity and such difference in pressure as may be developed under the circumstances on opposite sides of piston 13, to close quickly and by fluid pressure, thus synchronously close the disk valve 6.

The large by-pass directly through the piston 13 is formed by mounting the portion 80 piston 13 between a valve and a terminal stop on the piston rod 14 so as to permit slight play between the piston 13 and rod 14 and so that in pushing these parts together the valve will close the ports in the 85 piston 13 and in attempting to pull these parts asunder the ports will be opened by the valve. Lifting the dash pot 12 will then push the piston 13 and rod 14 together and so close the ports in piston 13 and so 90 induce positive pressure below piston 13.

To also provide for instances where pipe line conditions are such that the relief mechanism is not to be operated as a water saving device where disk valve 6 is closed 95 slowly, but is to perform the function of a water wasting synchronous disk valve by-pass, provision is made to couple the piston rod 14 with the dashpot casing 12. A pin can be inserted in one of the holes 20, 21, 22, 100 thus causing the disk valve by-pass to open either one-half, three-fourths, or fully, whenever the turbine gates or the impulse wheel needles are completely closed. In this case there is a slotted connection between the gates and the lever 9 in order to prevent buckling of the connection should the turbine gates be opened more than the corresponding setting of the dashpot coupling. The change from water-saving relief mechanism to synchronous by-pass can thus be done in a very simple manner even during operation of the unit.

What is claimed is,—

1. In a turbine, a penstock, gate mechanism controlling the flow of fluid from said penstock to said turbine, a by-pass for said turbine, a valve in said by-pass subject to penstock pressure to open same, a cylinder adjacent said by-pass, a stem on said valve 115 extending into said cylinder, a piston on said stem within said cylinder, means for admitting pressure to said cylinder on the valve side of said piston to close said valve, means for controlling the pressure for operation of said by-pass valve, and a mechanical connection between said gate mechanism and said controlling means including a dash pot casing, a piston coacting with said casing to form a chamber, leakage 120 125 130

- means from said chamber, and means providing for free flow of fluid to said chamber when relative motion between said casing and piston enlarges said chamber and preventing said free flow during opposite relative motion of said parts.
2. In a turbine, a penstock, gate mechanism controlling the flow of fluid from said penstock to said turbine, a by-pass for said turbine, a downwardly opening fluid pressure operated valve in said by-pass, a valve controlling the fluid pressure operation of said by-pass valve, and a mechanical connection between said gate mechanism and said controlling valve including a dash pot casing, a piston coacting with said casing to form a chamber, leakage means from said chamber, and means providing for free flow of fluid to said chamber when relative motion between said casing and piston enlarges said chamber and preventing said free flow during opposite relative motion of said parts.
3. In combination, a hydraulic pressure main, a main valve controlling the flow therethrough, operating mechanism for said main valve, a fluid downwardly opening pressure operated relief valve controlling an outlet from said main near said main valve on the pressure side thereof, a valve controlling the fluid pressure operation of said relief valve, and a mechanical connection between said main valve and said controlling valve including a dash pot casing, a piston coacting with said casing to form a
- chamber, leakage means from said chamber, and means providing for free flow of fluid to said chamber when relative motion between said casing and piston enlarges said chamber and preventing said free flow during opposite relative motion of said parts.
4. In combination, a hydraulic pressure main, a main valve controlling the flow therethrough, operating mechanism for said main valve, a downwardly opening valve controlling an outlet from said main near said main valve on the pressure side thereof, said relief valve being subject to the pressure in said main to open said relief valve, fluid pressure operated means for closing said valve, a valve controlling the degree of pressure of the fluid operating on said fluid pressure operated means, and a mechanical connection between said main valve and said controlling valve including a dash pot casing, a piston coacting with said casing to form a chamber, leakage means from said chamber, and means providing for free flow of fluid to said chamber when relative motion between said casing and piston enlarges said chamber and preventing said free flow during opposite relative motion of said parts.

In testimony whereof, I affix my signature in the presence of two witnesses.

ARNOLD PFAU.

Witnesses:

H. C. CASE,
W. H. LIEBER.

It is hereby certified that in Letters Patent No. 1,202,310, granted October 24, 1916, upon the application of Arnold Pfau, of Milwaukee, Wisconsin, for an improvement in "Gate-Coacting Relief Mechanism," an error appears in the printed specification requiring correction as follows: Page 3, line 27, claim 3, for the words "fluid downwardly opening" read *downwardly opening fluid*; and that the said Letters Patent should be read with this correction therein that the same may conform to the record of the case in the Patent Office.

Signed and sealed this 21st day of November, A. D., 1916.
